TELEVISION ANTENNA ROD FOR INDOOR USE

Marvin P. Middlemark, 96 Store Hill Road,
Old Westbury, N.Y. 11568

Filed Dec. 23, 1974, Ser. No. 535,197

Term of patent 14 years

Int. Cl. D14—03

U.S. Cl. D26—14 F

FIG. 1 is a front elevational view of a television antenna rod for indoor use showing my new design;

FIG. 2 is a top plan view thereof; and

FIG. 3 is a bottom plan view thereof.

I claim:

The ornamental design for a television antenna rod for indoor use, as shown.
